INVENTOR
LOFTUS LOWNDES,
BY *A. V. Jones*
ATTORNEY

UNITED STATES PATENT OFFICE.

LOFTUS LOWNDES, OF DUBLIN, IRELAND.

SASH-CORD FASTENER.

1,398,561.

Specification of Letters Patent. Patented Nov. 29, 1921.

Application filed November 4, 1919. Serial No. 335,734.

To all whom it may concern:

Be it known that I, LOFTUS LOWNDES, a subject of the King of Great Britain, residing at Dublin, Dublin county, Ireland, have 5 invented certain new and useful Improvements in Sash-Cord Fasteners, of which the following is a specification.

This invention relates to improvements in sash cord fasteners for securing balance- 10 weight cords or chains to up and down window sashes, sliding doors and similar structures.

The means heretofore employed for this purpose has been objectionable because it 15 has been necessary to dismember the window frames and remove their sashes therefrom in order to gain access to the said means.

The object of the invention is to overcome 20 this objection by the provision of a novel, simple and efficient fastener by means of which the sash cords or chains may be quickly attached to or detached from window sashes and the like, for repairs and 25 other purposes, and held in proper working relation thereto without the removal thereof from the frames in which they slide.

With the above and related objects in view, the invention consists in the novel construction and combinations of parts herein- 30 after described and claimed.

In the accompanying drawings, illustrating my invention,

Figure 1 is a front view, partly in section and broken away, of one of the upper corners of a window sash having a balance-weight cord attached thereto by a fastener embodying my invention.

Fig. 2 is an edge view thereof.

Fig. 3 is a horizontal section through the sash and fastener, on line 3-3 of Fig. 1.

Figs. 4 and 5 are front and side views, respectively, of the removable fitting of the fastener.

Figs. 6 and 7 are front and side views, respectively, of the permanent fitting of the fastener.

Referring to the drawings, 2 designates a portion of one of the upper corners of a 50 window sash, having a vertical groove 4 formed in the stile 5 thereof in the usual location for the reception of one end portion of the cord 6, by means of which that side of the sash is suspended, within a window frame, the other end portion of the

cord being adapted to be attached to a balance-weight, and the body of the cord being adapted to pass over a pulley journaled in the window frame when the sash is raised and lowered therein in the usual well known 60 manner.

My improved fastener comprises two fittings 7 and 8. The fitting 7 is permanently attached to the sash 2 and is adapted to receive and retain the fitting 8; and the fitting 8 is removable from the fitting 7 and the sash 2 and is provided with means for having the cord 6 attached thereto.

The permanent fitting 7 comprises a plate 9 and two spaced parts or arms 10 extending 70 therefrom. The plate 9 is recessed into the wall of the stile 5 adjacent to the lower end of the cord groove 4, and the plate 9 is secured to the stile 5 by screws 11 which penetrate the plate 9 and are screwed into the 75 stile 5, and which have countersunk heads seated in the plate 9, so as to present a smooth, uninterrupted outer edge face for the window sash. The arms 10 extend inwardly from the upper portion of the plate 9 and into the upper portion of the expanded lower end portion 12 of the groove 4, leaving a space between the bottom of the arms 10 and the bottom wall of the groove 4, as shown in Figs. 1 and 2. The bottom of 80 each arm 10 is formed with an inclined face 13 and a horizontal face 14, as clearly shown in Figs. 1 and 7, for a purpose hereinafter explained, and the opposing faces of the arms 10 form, in effect, continuations of the 85 side walls of the upper or narrow portion of the groove 4.

The removable fitting 8 comprises a long arm 15 having a head 16 formed on the lower end thereof and provided with parts 95 or projections 17 which extend outwardly from opposite sides thereof. The long arm 15 is made slightly concavo-convex in cross section, and the head 16 has a tapered opening 18 extending vertically therethrough. 100 The opening 18 is flared downwardly and outwardly and it is adapted to receive the lower expanded or knotted end 19 of the cord 6 and serve as a means for attaching the cord 6 to the fitting 8 by preventing the 105 enlarged or knotted end 19 of the cord from being drawn upwardly from within the opening 18. The end of the cord 6 may be expanded to form the enlarged end 19 by a wrapping applied to the cord, or by un- 110

raveling the end of the cord for a short distance and knotting the strands together, or in any other appropriate manner.

When the fittings 7 and 8 are in service, 5 fastening the end of the cord 6 to the sash 2, they occupy the position shown in Figs. 1, 2 and 3; the long arm 15 of the removable fitting extends from between the arms 10 of the permanent fitting up through the groove 10 4 to a point at or near the top of the sash 2 or upper open end of the groove 4, and the projections 17 of the removable fitting extend outwardly beneath and in engagement with the horizontal faces 14 of the arms 10 15 of the permanent fitting 7. The upward pull of the cord 6 holds the projections 17 in engagement with the arms 10 causing the cord 6 to support the sash 2; and the inclined faces 13 of the arms 10, engaging the projections 17, hold the removable fitting 8 back against the inner or base wall 20 of the groove 4. As the long arm 15 extends upwardly from the back of the head 16, the arm 15 lies flat against the base wall 20 and 20 leaves plenty of room in the groove 4 for the free working of the cord 6 in the usual manner.

In assembling the parts, the end of the cord 6 is expanded or knotted and passed 30 upwardly through the opening 18 in the removable fitting 8, outside of the sash 2, until the expanded end 19 of the cord is seated in the tapered opening 18. The fitting 8 is then inserted into the groove 4 from a position 35 above the sash 2 and with the fitting 8 turned a quarter turn from the position shown in Figs. 1, 2 and 3 to permit the head 16 and its projections 17 to pass down through the groove 4. The fitting 8 is then 40 lowered into the groove 4 until the head 16 passes down between the arms 10 and the top of the projections 17 are in a plane a little distance below the horizontal faces 14 of the arms 10 and at or near the lower ends 45 of the inclined faces 13 of the arms 10. The fitting 8 is now given a quarter turn to bring the projections 17 beneath the arms 10, and the fitting 8 is then drawn upwardly until the top of the projections 17 engage the 50 horizontal faces 14 of the arms 10, thereby locking the fittings 7 and 8 together and preventing the withdrawal of the lower end of the cord 6 from the lower portion of the groove 4. During this upward movement of 55 the fitting 8 to engage the projections 17 with the arms 10, the inclined faces 13 force the fitting 8 back against the base wall 20 of the groove 4, and, thereafter, retain the fitting 8 in such position. A reversal of the 60 operation just described will remove the fitting 8 and cord 6 from the sash 2; and either operation may be performed without removing the sash 2 from the frame in which it slides, because the fitting 8 may be manipulated from a position above the upper open 65

end of the groove 4 by the aid of any suitable tool or tools. The upper end of the long arm 15 of the removable fitting 8 has a hole 21 formed therein for the reception of a suitable tool or implement employed in 70 adjusting the fitting 8 while it is being applied to or removed from the sash 2.

The plate 9 of the permanent fitting 7 has a slot 22 formed therein which receives one of the projections 17 when the removable fitting 8 is applied to or removed from the permanent fitting 7. 75

I claim as my invention:

1. In a device of the character described, a window sash having a cord-receiving groove therein, a permanent fitting comprising a member having two spaced parts projecting therefrom, and a removable fitting extending between said parts and having a head provided with two parts projecting therefrom beneath the said parts of the permanent fitting and preventing its withdrawal therefrom, said removable fitting having a cord attached thereto and being removable from the sash when the said part of the removable fitting is moved from beneath the said parts of the permanent fitting by turning the removable fitting longitudinally. 80

2. In a device of the character described, a window sash having a cord-receiving groove therein, a permanent fitting comprising a member secured to the sash below the top thereof and having two spaced parts projecting therefrom, and a removable fitting comprising an arm extending between said parts and through said groove from the permanent fitting to a point near the top of the sash and two parts projecting from the lower portion of the arm beneath the said parts of the permanent fitting and preventing the withdrawal of the arm from the groove, said removable fitting having a cord attached to the lower portion thereof and being removable from the sash when the said parts of the removable fitting are moved from beneath the said parts of the permanent fitting by turning the removable fitting longitudinally. 90

3. In a device of the character described, a window sash having a cord-receiving groove therein, a permanent fitting comprising a plate member secured to one side of the sash opposite to the base of the groove therein below the top thereof and having two spaced parts projecting inwardly therefrom toward the base of said groove and above the lower end thereof, and a removable fitting comprising an arm extending between said parts and through said groove from the permanent fitting to a point near the top of the sash and two parts projecting from the lower portion of the arm beneath the said parts of the permanent fitting and preventing the withdrawal of the arm from the 100 105 110 115 120 125 130

groove, said removable fitting having a cord attached to the lower portion thereof and being removable from the sash when the said parts of the removable fitting are moved 5 from beneath the said parts of the permanent fitting by turning the removable fitting longitudinally.

4. In a device of the character described, a window sash having a cord-receiving groove therein, a permanent fitting comprising a plate member secured to one side of the sash opposite to the base of the groove therein and below the top thereof and having two spaced parts projecting inwardly therefrom toward the base of said groove and above the lower end thereof, said parts having substantially horizontal bottom faces connected to downwardly and outwardly inclined faces, and a removable fitting comprising an arm extending between said parts and through said groove from the permanent fitting to a point near the top of the sash and two parts projecting from opposite sides of the lower portion of the arm beneath and engaging the horizontal faces of the said parts of the permanent fitting and preventing the withdrawal of the arm from the groove, said removable fitting having a cord attached to the lower portion thereof and being removable from the sash when the said parts of the removable fitting are lowered and moved from beneath the said parts of the permanent fitting by turning the removable fitting longitudinally, and 35 said inclined faces of the permanent fitting engaging the said parts of the removable fitting and holding it back in said groove.

5. In a device of the character described, a window sash having a cord-receiving groove therein formed with a narrow upper portion and an expanded lower portion, a

permanent fitting comprising a plate member secured to one side of the sash opposite to the base of the expanded portion of said groove and having two spaced parts projecting therefrom into the expanded portion of said groove and forming continuations of the side walls of the narrow upper portion of said groove, and a removable fitting comprising an arm extending between said parts and through the narrow portion of the groove to a point near the top thereof and two parts projecting from opposite sides of the lower portion of the arm and into the expanded portion of said groove beneath the 45 said parts of the permanent fitting and preventing the withdrawal of the arm from the groove, said removable fitting having a cord attached to the lower portion thereof and being removable from the sash when the said 60 parts of the removable fitting are moved from beneath the said parts of the permanent fitting by turning the removable fitting longitudinally.

6. A fitting for sash cord fasteners comprising a vertical plate member provided with a bifurcated upper end and two spaced parts projecting from the respective sides of its bifurcated end having substantially horizontal faces spaced from the plate member and also having inclined faces extending downwardly from the horizontal faces toward the plate member.

7. A fitting for sash cord fasteners comprising a long arm provided with a head on one of its ends having projections extending outwardly from opposite sides thereof and also having a tapered opening extending therethrough.

In testimony whereof I affix my signature 80 hereto.

LOFTUS LOWNDES.
